UNITED STATES PATENT OFFICE.

EMIL P. STARY, OF CEDAR RAPIDS, IOWA.

GAS ENGINE.

Application filed September 10, 1920. Serial No. 409,446.

To all whom it may concern:

Be it known that I, EMIL P. STARY, a citizen of the United States, residing at Cedar Rapids, in the county of Linn and State of Iowa, have invented a new and useful Gas Engine, of which the following is a specification.

This invention differs from internal combustion engines as heretofore constructed in that, the pistons are caused to travel twice inward and twice outward to every revolution, thus providing a stroke of the piston for drawing the charge of gas into the cylinders, a stroke for compression, a stroke for combustion and a stroke for discharging the burnt charge from the cylinders for every revolution of the engine.

The primary object of the invention is to provide novel means for preventing the withdrawal of the pistons from the cylinders to cause the cylinders to rotate.

A further object of the invention is to provide an engine of this character which will be exceedingly smooth in its operation, and one in which the fuel consumption is reduced to a minimum.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a side elevational view of an engine constructed in accordance with the present invention.

Figure 2 illustrates a fragmental sectional view of one of the valve members constructed in accordance with the present invention.

Figure 3 illustrates a sectional view 45 through the engine, and

Figure 4 illustrates a sectional view taken at right angles to Figure 3.

Figure 5 illustrates a fragmental detail view disclosing the relation of the exhaust with the engine.

Referring to the drawings in detail, the reference character 5 designates the supports for the engine, which are disposed at oppo-

site ends of the engine, the support being provided with securing means indicated at 55 6, whereby the engine may be secured to a supporting member.

Each of the supports includes a bearing member 7, one of the bearings having connection with the supporting collar 8, which 60 in turn has connection with the hollow shaft 9 through the medium of the bolts 10, the hollow shaft 9 being of a length to extend an appreciable distance within the engine housing to be hereinafter more fully de- 65 scribed.

This hollow shaft 9 supports the cam ring 11 on which are integrally formed the cams 12, the cams being arranged to operate the valve members 13 which control the passage 70 of fuel to the cylinders, and which are operated by means of the valve stems 13' contacting with the cams 12, the cams being timed to operate the valves at predetermined intervals to cause the smooth and easy run- 75 ning of the engine.

The engine also includes a housing indicated at 14, which is keyed to the main shaft 15, as by means of the key 16, a portion of the housing operating between the flanges 18 80 of the member 19, thus insuring a leak-proof connection between the rotary housing and stationary members of the engine.

A plurality of cylinders indicated at 20, are carried by the housing, and are arranged 85 in suitable spaced relation with each other, each of the cylinders being provided with an integral intake pipe indicated at 21, there being provided the valve members 13' operating in the pipes 21 for controlling the pas- 90 sage of fuel to the cylinders.

These intake pipes 21 are in communication with the intake manifold indicated at 22, which has communication with a suitable carburetor, not shown, and which directs the 95 fuel to the compartment 23 disposed between the intake pipes 21 and intake manifold 22 to provide communication between the intake manifold and intake pipes.

Secured to the hollow shaft 9, as at 24, is 100 the stationary cam-formed trackway 25, which trackway accommodates the rollers 26 carried on the ends of the pivoted members 27 which are rotatable with the housing and cylinders, the arms having pivotal connection with the housing as at 30.

These members 27 are substantially triangular in formation and also have pivotal connection with the connecting rods 31, through the arms 31', which in turn have 5 pivotal connection with the pistons 32, so that movement of the pistons 32 will result in a relative movement of the members 27 and rods 31. These arms 27 also have pivotal connection with connecting arms 29, as 10 at 28, so that movement of the members 27 results in relative movements of the pistons to which said connecting arms 29 are pivotally connected will result in movement of rod 29.

15 An apron 33 is carried by the forward portion of each of the cylinders, and secured thereto as by means of the bolts 34, the aprons being curved and of lengths to embrace portions of the adjacent cylinder, 20 there being stops 35 carried by each of these aprons, the stops being disposed adjacent to the rear ends of the cylinders, and within the path of travel of the pistons to restrict movement of the pistons and prevent 25 them from passing from the cylinders, during the explosion strokes thereof. Each of the cylinders has communication with the exhaust pipe 36 through the manifold 37, so that the exhaust from the cylinders may be carried off to a position remote from the cylinders, the valves 13 being timed to open when the cylinders pass the exhaust pipe 37, to permit the exhaust 30 to pass outwardly from the cylinders.

35 In the operation of the device, assuming that the pistons are in positions as indicated by Figure 3 of the drawings, it will be seen that the piston indicated by letter B is at the point of its travel where the charge is under compression, the spark being set to ignite the charge at this point.

In this position the roller 26 abuts against the face of the cam-formed trackway 25, so that when the explosion takes 45 place in this cylinder, the piston is held against withdrawal from its cylinder, and the latter is thereby caused to rotate.

This rotation carries the roller 26 towards the axis of rotation on the cam-formed trackway 25, the cylinder reaching the limit of its outermost movement from the piston just as the roller 26 reaches the 50 point on the cam-formed track 25, which is nearest the axis of rotation. The cam-formed track then, by reason of its cam action on the roller 26, gradually forces the piston 32 inwardly, the piston reaching the limit of its innermost movement at the same time that the roller 26 reaches the 55 point on the cam-formed track 25, which is farthest from the axis of rotation, this inward movement of the piston discharging the burnt charge from the cylinder.

The piston 32 is gradually withdrawn 60 from the cylinder by means of the con-

necting arm 29 which is pivoted at one end to the roller end of the member 27, and at the other end to the roller end of the following member 27, the roller of this following member 27 now being at the point 70 on the cam-formed track 25 nearest the axis of rotation, from which point the roller 26 of the succeeding member 27 is gradually forced away from the axis of rotation, thus drawing the preceding roller 26 towards 75 the axis of rotation, which movement withdraws the piston from the cylinder, thereby drawing a charge into the cylinder.

The roller 26 is then gradually forced away from the axis of rotation which movement forces the piston inwardly thereby compressing the charge, the charge being fully compressed just as the roller 26 reaches the point on the cam-formed track 25 which is farthest from the axis of rotation at 85 which point the compressed charge is ignited and the above described operation is repeated.

It might be further stated that when the revolving cylinder reaches the point in its 90 travel where the piston begins its inward movement to discharge the burnt charge the outlet valve 13 is forced open by reason of its push-rod 13' being carried in contact with the stationary cam 12 and closed by 95 the spring 12' when the push-rod 13' clears the cam at the point where the piston has reached the limit of its inward stroke, the burnt charge being thus forced through the outlet valve 13, thence through the passage-way 36' and manifold 37 into the exhaust pipe 36. The cylinder now being at the point in its travel where the piston begins its outward movement, the inlet valve is forced open by its push-rod 13' being 100 brought into contact with a cam 12, the withdrawing piston, thus drawing a charge of gas from the carburetor through the manifold 22 and passage-way 22' leading to the opened inlet valve 13, which is closed by 105 its spring 12' at the point where the piston has reached the limit of its outward movement, by reason of its push-rod 13' clearing the cam 12, at this point. The piston then compresses the charge which is 110 ignited and the operation repeated, as above described.

Having thus described the invention, what is claimed as new is:—

In an internal combustion engine, a support, a stationary hollow shaft mounted on the support, a cam mounted on the hollow shaft, a shaft mounted within the hollow shaft, a housing keyed on the last mentioned shaft to revolve therewith, cylinders carried by the housing, substantially triangular pivoted members mounted within the housing, pistons having rods operating in the cylinders, arms having connection with the pivoted members, a roller mounted on each piv-

oted member and adapted to move over the cam, arms for connecting adjacent triangular pivoted members, arms for connecting the pivoted members and piston rods, and
5 said pivoted members adapted to move the rollers into engagement with the cam to rotate the housing.

In testimony that I claim the foregoing as my own, I have hereto affixed my signature in the presence of two witnesses.

EMIL P. STARY.
